Primary Examiner — Ryan Harvey(74) *Attorney, Agent, or Firm* — Chisholm Persson + Ball PC; Michael J. Persson; Catherine E. Napjus(57) **CLAIM**

The ornamental design for a weightlifting grip, as shown and described.

DESCRIPTION

FIG. 1 is a top perspective view of the weightlifting grip in an open position.

FIG. 2 is a top elevation view of the weightlifting grip.

FIG. 3 is a bottom elevation view of the weightlifting grip.

FIG. 4 is a front plan view of the weightlifting grip.

FIG. 5 is a back plan view of the weightlifting grip.

FIG. 6 is a right side plan view of the weightlifting grip; and,

FIG. 7 is a left side plan view of the weightlifting grip.

The broken lines in all figures represent stitching that forms part of the claim.
